(57) **CLAIM**

The ornamental design for a bottle, as shown and described.

DESCRIPTION

FIG. 1 is a front perspective view of a first embodiment of the bottle with a translucent teat;

FIG. 2 is a front elevational view thereof;

FIG. 3 is a rear elevational view thereof;

FIG. 4 is a right side elevational view thereof;

FIG. 5 is a left side elevational view;

FIG. 6 is an enlarged top plan view thereof;

FIG. 7 is an enlarged bottom plan view thereof;

FIG. 8 is a front perspective view of a second embodiment of the bottle;

FIG. 9 is a front elevational view thereof;

FIG. 10 is a rear elevational view thereof;

FIG. 11 is a right side elevational view thereof;

FIG. 12 is a left side elevational view;

FIG. 13 is an enlarged top plan view thereof; and,

FIG. 14 is an enlarged bottom plan view thereof.

The broken lines in the drawings depict portions of the transition cup top that form no part of the claimed design.

1 Claim, 14 Drawing Sheets
